CONTAINER

Filed Jan. 9, 1922

FIG. 5

INVENTOR

BY *Michael Todaro*

ATTORNEY

Patented June 17, 1924.

1,497,960

UNITED STATES PATENT OFFICE.

MICHAEL TODARO, OF BROOKLYN, NEW YORK.

CONTAINER.

Application filed January 9, 1922. Serial No. 527,995.

To all whom it may concern:

Be it known that I, MICHAEL TODARO, a citizen of the United States, residing in the borough of Brooklyn, county of Kings, city and State of New York, have invented certain new and useful Improvements in Containers, of which the following is a specification.

My invention relates to containers, and it particularly relates to containers for substances in liquid, powder or paste form, which are continually used in relatively small quantities and must be well protected against the influence of the atmosphere.

Another object of the invention is to provide a container for household use that can be easily refilled, and may be substituted, for instance in the case of milk, for open pitchers, or the original tin cans, the cover of which one has to provide with two holes usually left open until the can is emptied. This latter method is the cause of waste in so far as such sensitive substances like milk are then affected by the unrestricted admission of air into the container, the substance either being completely spoiled or partly destroyed, for instance, also by the evaporation of volatile matter.

These and other objects of the invention will be more fully apparent from the following description, reference being had to the accompanying drawings, in which—

Fig. 1 is a top view of the uncovered container,

Fig. 2 is a front elevation of the uncovered container,

Fig. 3 is a top view of the cap covering the container,

Fig. 4 is a front elevation of the cap, and

Fig. 5 is a vertical sectional view of the opened container on line Z—Z of Figure 1.

Like numerals refer to like parts throughout the several views.

Referring to the drawings, 1 denotes a cylindrical container or jar, made of glass, porcelain, or any suitable metal like aluminum, silver, etc., with a screw threaded neck 2, and a lip 3, slanting preferably at an angle of 45 degrees. In this slanting lip 3, holes 4 and 5, serving as an outlet for the substance and an inlet for the air respectively or vice versa, are provided diametrically opposite each other. A cap 6, consisting of the screw threaded side wall 7, the slanting face 8, and the cover 9, surrounds the neck 2 of the container. Holes 10 and

11 are provided diametrically opposite each other in the slanting face.

In the position illustrated by Figure 5, holes 10 and 4 as well as holes 11 and 5 register with each other, because in this position the cap 6 is slightly turned backward or unscrewed, the annular dotted line 12 indicating the spot where hole 10 will be located when by a slight turn to the right as indicated by arrow A (see Figures 2 and 4) cap 6 is screwed tight, the metal of the slanting face 8 thus closing hole 4. Holes 5 and 11 are standing in the same relation to each other as holes 4 and 10 respectively, it appearing as if hole 11 moves from the right to the left when cap 6 is screwed tight.

In Figure 2, arrow B indicates the location of the hole 11, marked by an annular dotted line, when a slight turn of the cap 6 in the direction of arrow A closes the container, i. e., hole 11 will be right above the end of the screw thread of neck 2, while a turn in the opposite direction when the container is opened will cause hole 11 to register with hole 5. An inspection of Figure 4 shows that the cap 6 is constructed and formed in such manner that it will follow all the movements described above and that the end of its screw thread 7 will register with the end of screw thread 2, causing hole 11 to take the position shown in Figure 2 when the container is closed.

The container described above is intended preferably for use in connection with liquids, though it serves just as well for substances in powder or paste form. I modify, however, the construction of the container for powders and pastes slightly within the principle of the construction described above in connection with the container intended preferably for liquids.

The powder container differs only in that the lip is wider and reaches more towards the centre of the mouth of the container, and that the lip stands at an angle of 90 degrees to the neck or side of the container, and in that it has several perforations about the inner side of the lip with corresponding perforations in the cover. Furthermore, the slanting face 8 of cap 6 of the container for liquids merges in the container for powder with the cover 9.

The paste container or tube differs from the container for liquids in that only hole 5 of container 1 and hole 11 of cap 6 are used in the tops of these parts and in that said

tops are otherwise entirely sealed and lie at an angle of 90 degrees to the side walls of the container and cap respectively.

What I claim is:

- 5 As an article of manufacture a refillable container consisting of a jar of suitable material having a screw threaded cylindrical neck, an annular inwardly extending slanting lip at its mouth, two openings in said lip diametrically opposite each other, and a screw threaded cap conforming to the shape

of the mouth and having two openings diametrically opposite each other in the slanting face thereof, said openings in both the jar and the cap being disposed with reference to each other, so that the container is sealed when the cap is completely screwed on the jar and so that the openings register forming an air inlet and a liquid outlet for pouring out contents only by slightly unscrewing the cap on the sealed container. 15 20

MICHAEL TODARO.
